(57) **CLAIM**

The ornamental design for a ball manipulating device, as shown and described.

DESCRIPTION

FIG. 1 is a front, left perspective view of a ball manipulating device showing my new design;

FIG. 2 is a front, left perspective view thereof, in an open position;

FIG. 3 is a rear elevational view of FIG. 1;

FIG. 4 is a left side elevational view of FIG. 1, the right side being a mirror image;

FIG. 5 is a left side elevational view of FIG. 2, on a reduced scale;

FIG. 6 is a top plan view of FIG. 1;

FIG. 7 is a bottom plan view of FIG. 1; and,

FIG. 8 is a bottom plan view of FIG. 2.
